UNITED STATES PATENT OFFICE.

THOMAS S. DISSTON, OF PHILADELPHIA, PENNSYLVANIA, ASSIGNOR OF
ONE-HALF TO ALBERT S. CARTER, OF SAME PLACE.

CONVERTIBLE SKATE.

SPECIFICATION forming part of Letters Patent No. 329,146, dated October 27, 1885.

Application filed May 19, 1885. Serial No. 166,030. (No model.)

To all whom it may concern:

Be it known that I, THOMAS S. DISSTON, a citizen of the United States, and a resident of Philadelphia, Pennsylvania, have invented
5 certain Improvements in Convertible Skates, of which the following is a specification.

The object of my invention is to construct an attachment whereby the roller-spindle and its bearings can be readily and securely attached
10 to the ordinary runner of an ice-skate, my invention consisting of certain novel features of construction fully described and claimed hereinafter.

In the accompanying drawings, Figure 1 is
15 a side view of an ice-skate with my improved roller attachments, one of the latter being shown in section; Fig. 2, a transverse section on the line 1 2, Fig. 1, looking in the direction of the arrow; and Fig. 3, a perspective view showing the various parts of the attachment separated from each other.

A is the runner of an ordinary ice-skate, the sole-plate and the clamping devices of which may be constructed in any of the usual ways,
25 as they form no part of my invention, the latter relating only to the roller attachments. Each of these attachments consists of a clamp, B, which, as shown, is composed of a bent plate of metal, the plate being so shaped that after
30 it is bent it will present opposite wings for embracing the runner A, the roller-spindle D and its bearings being contained within a central recess, a, of the clamp.

The clamp is secured to the runner of the
35 skate by transverse bolts F and nuts F', these bolts passing through openings in the clamp beneath the runner of the skate, so that the clamp is secured to the runner by friction only, the formation of bolt-holes or other openings
40 through the runner being thus rendered unnecessary.

A supplementary bolt may pass through the clamp at a point above the runner, if desired; but this is not at all necessary.

45 One of the bolts F serves to secure in position a bar, G, which is interposed between said bolt and the bottom of one leg of the clamp B, a similar bar, H, being interposed between the opposite bolt and the bottom of
50 the other leg of the clamp. (See Fig. 1.) The

bar G has a bent end, b, in which is an opening forming a bearing for the spindle d of the plate J, the latter being forked, so as to form two bearings, ff, for the roller-spindle D, and having near each end a recess, h, for the reception of the lower end of a spring, g, of rubber or other suitable elastic material, the upper ends of the springs being adapted to sockets K, bolted, riveted, or otherwise secured to the opposite sides of the clamp B. As each spring is thus laterally confined at each end, accidental displacement of said springs is prevented.

The plate J and its spindle are arranged at such an angle to the roller-spindle D as to permit the desired compound swing of the roller-spindle—that is to say, when pressure is exerted upon the roller on one side of the skate and an upward movement is imparted to the end of the spindle carrying said roller, there will be at the same time a forward movement of that end of the roller-spindle, so as to permit the skates to travel in a curve.

The roller-spindle has a central bearing in a box, i, forming part of the bar H, and in order to permit the necessary swing of the roller-spindle this box has conical flares extending from the center of the box to each side of the same. This additional bearing for the roller-spindle serves to relieve the pivot-spindle d of the plate J from a portion of the strain which would otherwise be exerted upon said spindle.

The bearing i is so constructed as to bear upon the bottom of the runner A of the skate, so that there can be no vertical spring of the center of the roller-spindle in the event of excessive pressure upon the skate.

The clamp B may, if desired, be made of cast-steel or malleable iron, and in such case the bearing i and plate b may be cast with the clamp; but it is preferred to form the clamp by bending and to provide separate bars carrying the bearings i and b, as the parts can in such case be struck up by suitable dies out of sheet metal, and the manufacture of the attachment is facilitated.

I claim as my invention—

1. The combination of a clamp adapted to the runner of an ice-skate, a pivoted plate, J,

carrying bearings for the roller-spindle, sockets K, secured to the opposite sides of the clamp, and springs g, contained in said sockets, and bearing upon the plate J near its opposite ends, as set forth.

2. The combination of the clamp, the roller-spindle, the springs g, the sockets K, and the bearing-plate J, having recesses h for the springs, as set forth.

10 3. The combination of the roller-spindle, a fixed central bearing therefor having opposite conical flares, and a pivoted plate, J, having bearings for the spindle on each side of said central bearing, as specified.

15 4. The within-described clamp, having opposite wings for embracing the runner of a skate, and a central recess for the reception of a roller-spindle and its bearings, as specified.

20 5. The combination of a clamp adapted to

the runner of an ice-skate, a pivoted plate, J, having bearings for a roller-spindle, a bar, G, having a bearing for the pivot of said plate, and a bar, H, carrying a central bearing for the roller-spindle, as specified.

25

6. The combination of a clamp adapted to the runner of an ice-skate, a pivoted bearing-plate, a bar, G, having a bearing for the pivot of said plate, a bar, H, having a central bearing for the spindle, and bolts F, whereby the clamp is secured to the runner and the bars G and H secured to the clamp, as set forth.

30

In testimony whereof I have signed my name to this specification in the presence of two subscribing witnesses.

35

THOS. S. DISSTON.
